UNITED STATES PATENT OFFICE

JOHN C. BROOKS, OF PATERSON, NEW JERSEY

NEEDLE LOOM

Application filed November 21, 1927. Serial No. 234,721.

My invention relates to operating the filling inserting needles for looms.

One object of my invention is to enable two ply, or two separate fabrics, to be woven 5 one above the other, to best advantage on needle looms.

Another object is to provide a simple quick action of the needles in weaving very wide fabrics.

10 A further object is to provide a needle loom capable of more general use for weaving all kinds of fabrics.

I attain these objects by, in this instance, mechanism shown in accompanying drawings and described and claimed in this specification.

Fig. 1 is a front view, in elevation, of sufficient parts of the loom to illustrate my invention.

20 Fig. 2 is a side view of one of the brackets.

Fig. 3 is a similar view of the same brackets with the port holes operating mechanism attached thereto.

Fig. 4 is a longitudinal sectional view of 25 a part of the air cylinder with a portion of one of the needles.

Fig. 5 is a side view of the filling engaging end of the needle.

Fig. 6 is a cross section view of the needle 30 through dotted line XX of Fig. 5.

Figs. 7 and 8 are top and side views, respectively of the port hole caps.

Fig. 9 is a side view of one form of cam, lever and rod, to operate the mechanism.

35 Construction: Secured on rear of batten A are vertical brackets 1, 2, provided with holes 3, 4, 5, 6. Supported in holes 3, 6, and secured therein by screws 7, 8, are air receiving cylinders 9, 10, provided with threaded caps 11, 12, 13, 14, having air inlets, 15 and air ports, 16, 17.

Pivoted on brackets 1, 2, are port caps, 18, 19, provided with mats, 20, 21, and in their free ends slots 22. Engaging in said slots 45 22 is a rod 23, provided with spiral springs 24, 25, held in adjustable tension by collars 26, 27. Also on rod 23 are collars 28, 29, engaging below slots 22 of caps 18, 19.

Supported in holes 4, 5, are shafts 30, 31, 50 provided with slotted arms 32, 33, between

which passes rods 23. Above and below said slotted arms are collars 34, 35, secured on said rods 23.

At the outer end of shaft 30 is a lever arm 36, provided with rod 37, engaging a lever 38, operating an air cock 39, provided with an air inlet 40, connected to any source of suitable air supply.

Secured to air cock 39 are pipes 41, 42, leading into their respective cylinders 60 through caps 11 and 13.

At the inner end of shaft 31, is an arm 43, rod 44, lever 45, air cock 46, inlet 47, and tubes 48, 49, joining said cock 46 to air cylinders through caps 12, 14.

65 Secured on shaft 30 is a lever arm 50, provided with a rod 51, engaging a lever 52, pivoted to the loom frame and provided with a roller 53, engaging in a cam 54, secured on loom shaft B. On shaft 31 is a lever arm 55, rod 56, lever 57, with a roller engaging within cam 58 on shaft B.

70 On the butt or head end of the needle 60 is secured a flange 61, against which is placed a flexible washer 62, lapping over edges of 75 flange 61. A second flexible washer 63, is placed next to washer 62 but overlapping a loose flange 64. A nut 65, serves to secure these flanges and washers together and form a double acting piston with which to recipro- 80 cate the needles.

The needles are flattened as at 66, Fig. 6, to prevent the rotation during operation; the caps 12, 14 having corresponding holes therefor.

85 The long filling eye, 67, serves to slightly slacken the filling thread to facilitate the action of the filling catching needle, or the edge forming shuttle in general use in needle looms.

The enlarged under portion, 68, serves to support and guide the needles when weaving very wide fabrics.

90 The cam 54 operates to open cock 39 and inner ports to project the needles within the warp sheds. Cam 58 opens cock 46 and outer ports to return the needles to their normal position.

95 The location of ports with respect to the ends of the air cylinders, is determinative by 100

the speed of operation and amount of cushioning desired.

While the mechanism is shown as attached to one end of the loom, it is obvious that a duplication could be made at the other end. The operation of the device will be readily understood from the foregoing description. The cam 54 operates through the connection 51 and 50 to rock the arm 30 and as the arm is rocked in one direction the valve 39 is opened to admit compressed air to the right-hand end of the cylinders 9 and 10 and simultaneously the left-hand rod 23 is raised thereby opening the exhaust ports at the left-hand end of the cylinders. This will cause the piston to move toward the left thereby projecting the needles 60 through the sheds. As the shaft B continues to rotate, the shaft 30 will be actuated to close the valve 39 and to lower the rod 23 to close the exhaust ports at the left-hand end of the cylinders.

The rotation of the cam 58 will operate through the connections 56 and shaft 31 to open the valve 46 to allow compressed air to enter the left-hand ends of the cylinders and at the same time the exhaust valves at the right-hand end of the cylinders will be opened whereby the needles are withdrawn from the sheds.

30 The device, therefore, has means common to one inlet valve and the corresponding exhaust valves to operate them simultaneously, and other means common to the other inlet valve and the corresponding exhaust valves to operate them simultaneously.

Having described my invention, I claim—

1. In a loom, the combination with a bat-
ten, of two cylinders carried thereby, one
above the other, a piston in each cylinder, a
40 weft-inserting needle actuated by each pi-
son, two separate inlet valves, one controlling
the admission of compressed air to one end of
both cylinders and the other controlling the
admission of compressed air to the other end
45 of both cylinders, each cylinder having ex-
haust valves, means common to one inlet valve
and the corresponding exhaust valves to operate
them simultaneously, other means com-
mon to the other inlet valve and correspond-
50 ing exhaust valves to operate them sim-
ultaneously and devices to actuate said means
alternatively.

2. In a loom, the combination with a bat-
ten, of two cylinders carried thereby, a pi-
son in each cylinder, a weft-inserting needle
actuated by each piston, two separate inlet
valves, one controlling the admission of com-
pressed air to the same end of both cylinders
and the other controlling the admission of
55 compressed air to the other end of both cy-
linders, each cylinder having two exhaust
ports, an exhaust valve for each port, two
rock shafts, connections between one rock
60 shaft and one inlet valve and the correspond-
ing exhaust valves, and between the other rock

shaft and the other inlet valve and corre-
sponding exhaust valves, and means for oper-
ating said shafts to cause the inlet valves to
be opened alternately and the exhaust valves
in timed relation with the inlet valves.

3. In a loom, the combination with a bat-
ten, of two cylinders carried thereby, a pi-
son in each cylinder, a weft-inserting needle
actuated by each piston, means for admit-
ting compressed air to said cylinder simul-
70 taneously thereby to simultaneously actuate
the pistons, each piston having an exhaust
port in its side, a pivoted valve for each ex-
haust port, each valve having a slotted arm,
an actuating rod operating in the slots of the
75 arms, and means for actuating said rod in
timed relation with the operation of the inlet
valve.
